UNITED STATES PATENT OFFICE

WILLIAM L. MYERS, OF NEWARK, NEW JERSEY, ASSIGNOR TO L. A. MYERS, JR., INC.,
OF NEWARK, NEW JERSEY, A CORPORATION OF NEW JERSEY

DESIGN FOR A BUCKLE

Application filed August 2, 1929. Serial No. 32,274. Term of patent 7 years.

To all whom it may concern:

Be it known that I, WILLIAM L. MYERS, a citizen of the United States, residing at Newark, in the county of Essex and State of New Jersey, have invented a new, original, and ornamental Design for Buckles, of which the following is a specification, reference being had to the accompanying drawing, forming part hereof.

Figure 1 is a plan view of a buckle, showing my new design and Fig. 2 is an edge elevation of the same.

I claim:

The ornamental design for a buckle, as shown.

WILLIAM L. MYERS.
